UNITED STATES PATENT OFFICE.

JOSEPH W. C. SHIPMAN, OF LOS ANGELES, CALIFORNIA.

PHOTOGRAPHIC PRINTER.

1,369,560.

Specification of Letters Patent. Patented Feb. 22, 1921.

Application filed May 7, 1919. Serial No. 295,798.

To all whom it may concern:

Be it known that I, JOSEPH W. C. SHIPMAN, a subject of the King of Great Britain, residing at Los Angeles, in the county 5 of Los Angeles and State of California, have invented a new and useful Photographic Printer, of which the following is a specification.

My invention relates to the art of photographic printing, and the principal object 10 of my invention is to provide a photographic printer for printing upon rolls of sensitized paper, the apparatus being so constructed that it can be regulated to feed 15 the paper to suit the length of print desired.

A further object of the invention is to provide such a printer which will be very simple to manipulate and be especially 20 adaptable to the production of duplicate pictures in large numbers.

Referring to the drawings, which are for illustrative purposes only,

Figure 1 is an elevation partly in section 25 on a plane 1—1 of Fig. 2, showing one embodiment of my invention.

Fig. 2 is a cross-section on the plane 2—2 of Fig. 1.

Fig. 3 is a plan view of my invention.

30 Fig. 4 is a cross-section on line 4—4 of Fig. 1.

Fig. 5 is a cross-section on the line 5—5 of Fig. 3.

Fig. 6 is a diagram of connections.

35 Fig. 7 is a detail of a contact finger.

Fig. 8 is a plan view on an enlarged scale showing the gear train.

In the form of the invention illustrated 40 in the drawings, a light box 11 is provided this light box having a plurality of incandescent lamps 12 therein, one at least of which, 13, may conveniently be a red light. The top of the light box 11 may be closed by a plate of glass 14 upon which a negative 45 15 may be secured by any convenient means.

A roll of sensitized paper is placed in a box 20 upon a roller 21, this box having a hinged lid 22 which has a slot 23 through which the paper is drawn, this paper passing 50 over the top of the negative 15 with its sensitized side down, being held in contact therewith at either side of the negative by means of small rollers 24. The paper then passes between friction roll 25 and a driving 55 roller 26 to a roller 27 having a slot 28

therein in which the end of the paper may be secured.

The whole apparatus is supported on a supporting structure 30. Sliding in the structure 30 are two rods 31, these rods being secured at their upper end to a frame 32 to which are secured four rods 33 which carry a platen 34. The rods 31 pass through a cross-piece 35 and have compression springs 36 therearound, these springs tending to hold the frame 32 in its upper position as shown in Fig. 2.

A pedal 37 is provided connected to the rods 31 and by means of which they can be pushed downwardly thus pulling the frame 70 32 downwardly. The pedal 37 is also connected through braces 38 to the opposite side of the frame 32 to insure stiffness. For the purpose of regulating the travel of the pedal 37 collars 40 are provided on the rods 75 31, these collars having set screws 41 by means of which they can be secured in any position along the rods so that the upper position of the platen 34 above the negative 15 can be easily regulated, the platen 80 in any case going down until it rests upon the paper on top of the negative 15.

The platen is provided with a sheet of felt 45 or other resilient material and with four holding fingers 46 having the form 85 shown in Fig. 7. A movable contact 48 is provided on the frame 32 and a stationary contact 49 is provided on the frame 30, these contacts being so placed that they are in electrical connection with each other 90 when the felt 45 rests on the paper on top of the negative 15.

The lamps 12 are connected as shown in Fig. 6 to two wires 50 forming a source of electrical supply so that these lights are 95 energized whenever the contacts 48 and 49 touch. An auxiliary switch 51 may be provided for lighting the lights at other times, and an auxiliary switch 52 may be provided for lighting the red lamp alone.

The rolls and paper are driven through a rack 60 which is secured on the side of the frame 32 and which actuates a gear 61 fixed to a shaft 59, an idler 62 and a gear 63. The gear 63 carries pins 64, each of which carries a pawl 65. These pawls 65 engage a ratchet wheel 66 which is secured to a second ratchet wheel 67 which in turn is secured to the roller 26. A belt wheel 70 fixed to the shaft 59 drives a second belt wheel 71 110

through a belt 72. The belt wheel 71 is loose on a shaft 73 and is frictionally engaged by fingers 74 which are rigidly secured to the shaft 73. This shaft passes 5 through a bearing 75 in the frame 30 and carries a ratchet wheel 76 engaged by a ratchet 77. The roller 27 has a square shank fitting into the ratchet 76 and has a round shank 78 fitting into a spring bearing 79 10 carried in the frame 30 so that the roller 27 can be removed whenever it is filled with paper. The ratchet wheel 67 is engaged by a stationary pawl 80 carried on the frame 30.

The method of operation is as follows:

15 The pedal 37 being depressed, the platen 34 is pulled downwardly until the fingers 46 touch and hold the paper on top of the negative 15 and until the felt 45 presses solidly against this paper holding it in intimate contact with the negative. Whenever this occurs the contacts 48 and 49 engage, the lights 12 are energized, the light passing through the negative 15 onto the paper and making a photographic image 20 thereon. Upon releasing the pedal 37 the frame 32 rises due to the springs 36, the lights are turned off and the wheels 61, 62 and 63 turn, thus turning the ratchet wheel 66 by means of the pawls 65. This drives 25 the roller 26 in a clock-wise direction as shown in Fig. 1, the roller 26 coöperating with the roll 25 to feed the paper from left to right across the negative 15. At the same time the roller 27 being frictionally driven 30 through the finger 74 and the belt 72, winds up this paper on the roller 27. Upon pushing downwardly on the pedal 37 the pawls 65 slip on the ratchet wheel 66 which is held from turning due to the fact that it is connected to the ratchet wheel 67 which is 35 caught by the pawl 80. As a result the paper is not moved during the downward travel of the platen. The roller 27 is also held from turning on its downward movement by means of the ratchet wheel 66 and the pawl 77.

As the paper is only driven on the up stroke of the platen it is evident that the distance that the paper is driven can be 40 regulated by regulating the travel of the platen. This is accomplished by setting the collars 40 on the rods 31, these collars limiting the upward movement of the platen to any desired degree.

45 The platen 34 is hinged to the rods 33 as shown so that it can be readily turned back to give access to the negative 15.

What I claim is:—

1. A photographic printer comprising a

supporting structure; a light box fixed in 60 said structure; a luminous source fixed in said box; means for supporting a negative over said box; means for holding a strip of sensitized paper loosely in contact with said negative; a platen normally held above said 65 negative; means for forcing and holding said platen against said paper; means for energizing said luminous source when said platen is so pressed; rollers for feeding said paper across said negative; a rack secured 70 to and moving in synchronism with said platen; a gear wheel mechanism driven by said rack; and means by which said gear wheel actuates said rollers.

2. A photographic printer comprising a 75 supporting structure; a light box fixed in said structure; a luminous source fixed in said box; means for supporting a negative over said box; means for holding a strip of sensitized paper loosely in contact with said 80 negative; a platen normally held above said negative; means for forcing and holding said platen against said paper; means for energizing said luminous source when said platen is so pressed; rollers for feeding said 85 paper across said negative; a rack secured to and moving in synchronism with said platen; a gear wheel mechanism driven by said rack; pawls carried by said gear wheel 90 mechanism; a ratchet wheel driven in one direction only by said pawls; and means by which said ratchet wheel drives said rollers.

3. A photographic printer comprising a supporting structure; a light box fixed in 95 said structure; a luminous source fixed in said box; means for supporting a negative over said box; means for holding a strip of sensitized paper loosely in contact with said negative; a platen normally held above said negative; means for forcing and holding 100 said platen against said paper; means for energizing said luminous source when said platen is so pressed; rollers for feeding said paper across said negative; a rack secured to and moving in synchronism with said 105 platen; a gear wheel mechanism driven by said rack; pawls carried by said gear wheel mechanism; a ratchet wheel driven in one direction only by said pawls; a stationary 110 pawl preventing said ratchet wheel from turning in the opposite direction; and means for securing said ratchet wheel to one of said rollers.

In testimony whereof I have hereunto set my hand at Los Angeles, California, this 115 2nd day of May, 1919.

JOSEPH W. C. SHIPMAN.
